CABINET FOR MESSAGE DISPLAY PANEL

David E. Liddle, Toledo, and George W. Lambroff,
Swanton, Ohio, assignors to Owens-Illinois, Inc.

Filed Dec. 22, 1970, Ser. No. 26,616

Term of patent 14 years

Int. Cl. D14—02; D20—03
U.S. Cl. D96—12

FIG.1

FIG.4

FIG. 1 is a perspective view taken from the front, top and one end of a cabinet for message display panel showing our new design;

FIG. 2 is a perspective view taken from the rear, top and end opposite that shown in FIG. 1;

FIG. 3 is a front elevational view thereof; and

FIG. 4 is a bottom plan view thereof.

We claim:

The ornamental design for a cabinet for message display panel, as shown.
